NONREFILLABLE BOTTLE

Walter Keenan, Little Falls Township,
Passaic County, N. J.

Application March 23, 1936, Serial No. 70,306

1 Claim. (Cl. 215—21)

My application relates generally to non-refillable bottles or devices adapted to be attached to the neck of ordinary bottles to prevent refilling said bottle.

5 The main object of the device is to provide a one-way valve allowing liquid to be poured out of the bottle but prevent the bottle from being refilled. A further object is to provide a valve cage, with orifices and passages therein through which 10 the liquid may be discharged but at the same time prevent manual tampering with the valve in attempting to refill the bottle, by virtue of the novel design and location of said orifices and passages.

15 The valve is a ball, and is held in said cage which has the general form of a truncated cone. The object of said cone shaped cage is to provide means for rolling the ball valve toward the valve seat even when the bottle and device are 20 held in a horizontal position thereby tending to close the valve against the possibility of attempting to introduce liquid into the bottle even in this position.

The construction and operation of the device 25 are explained in the following description in conjunction with the accompanying drawing, wherein:

Fig. 1 is a front elevation in section of the device attached to a bottle neck.

30 Fig. 2 is a front elevation of the valve cage and Fig. 3 is a plan view thereof.

Fig. 4 is a plan view of the valve seat bushing and Fig. 5 is a front elevation thereof.

In Fig. 1, numeral 1 indicates the tubular housing having the lower portion of the internal wall (which fits over the bottle neck) parallel with the longitudinal axis; the upper portion is tapered toward the throat or discharge outlet 18. The ball valve cage 2 comprises a body portion 40 having the shape of a truncated cone terminating at the smaller end in a head plate 5. The said head plate 5 is larger in diameter than the conical body 21 at this point and is provided with a plurality of normally vertical orifices 8 parallel 45 with the longitudinal axis of the cage 2 and located adjacent the periphery of said head plate 5. The said vertical orifices 8 lead from a cone shaped annular passage 16, formed between the 50 internal surface of housing 1 and the external surface of valve cage 2, to the throat or discharge outlet 18. Adjacent the lower end of the conical body 21 a plurality of normally horizontal orifices 9 are provided which are perpendicular to the 55 longitudinal axis of said cage 2. The horizontal

orifices 9 lead from the conical valve chamber 7 to the cone shaped annular passage 16.

The lower end of the body 21 terminates in the base plate 6 which is provided with a central opening 20 (Fig. 2) through which the ball valve 3 will pass in assembling the device. A valve seat bushing 10, having a nipple portion 19, provides a seat 11 for said ball valve 3. The nipple portion 19 is adapted to fit snugly into the opening 20 and be retained therein by a press fit whereby the upper surface 14 of flange 13 is held against the base plate 6. The neck of the bottle 4 is forced up against the lower surface 15 of flange 13 to secure the cage assembly in the housing 1. A cementing material is then placed 10 in the area 17 around the neck of the bottle for 15 permanently fastening the housing 1 to the bottle 4.

When the bottle is held in a vertical position the ball valve 3 rests on the valve seat 11 as 20 illustrated in Fig. 1. When the bottle is tipped to an angle of approximately 70 degrees from the vertical for the purpose of pouring out the liquid, the ball valve 3 will roll from its seat 11 and rest against the inner wall of the cone shaped 25 cage 2. When the bottle neck has been tipped to a position of approximately 10 degrees below the horizontal, the ball valve 3 will roll to a position as shown in dotted lines in Fig. 1 and allow full 30 opening of the valve aperture 12. In the various 35 positions of the bottle between the said 70 degrees from the vertical and 10 degrees below the horizontal, after the ball valve 3 has been rolled from its seat, the said valve rests at one point 40 on the inner surface of the body 21 or chamber 35 7 and at another point on the valve seat 11. In that position a small partial opening exists between the valve 3 and seat 11 around the upper portion of the periphery. This small opening, in conjunction with the position of the bottle (70 45 degrees or more from the vertical), makes it impractical to refill the bottle even when the valve 3 is not fully seated.

As pointed out above the orifices 8 are parallel 45 with, and the orifices 9 perpendicular to the longitudinal axis of the cage 2; therefore due to the said orifices being at right angles to each other it is practically impossible to insert a wire or other instrument through the outlet and discharge passages for the purpose of dislodging 50 the valve 3 from its seat 11 in attempting to refill the bottle. Further due to the slope of the annular passage 16 the outer openings of the orifices 9 are a greater distance from the longitudinal axis of the cage than the distance be- 55

tween the orifices 8 and the said axis; therefore to insert a wire as aforesaid it would have to be bent to an acute angle.

When the valve 3 is rolled from its seat 11 the liquid from the bottle 4 flows from the bottle neck through the valve aperture 12 into the valve chamber 7 and thence through orifices 9, annular passage 16, orifices 8 and out at the throat 18.

In order to assemble the device, first a ball valve 3 is placed in the cage 2 and the valve seat bushing 10 pressed into position. Then the valve cage assembly is forced up into the body 1; the peripheral surface of the head and base plates 5 and 6 are beveled to conform with the internal 15 taper of the tubular housing 1 to provide a tight fit. The neck of the bottle 4 is then inserted in the lower end of the tubular housing 1 until it presses securely against the lower surface 15 of the valve bushing 10. While the said parts are held in this position a cementing compound is poured or forced into the area 17 between the housing and bottle neck to permanently fasten the device to the bottle.

It will be understood that the invention is not to be limited to the specific construction or arrangement of parts shown but that they may be widely modified within the invention defined by the claim.

I claim:

30 The combination with a bottle of a device for rendering the bottle non-refillable, comprising a tubular housing having the lower portion of the internal wall parallel with the longitudinal axis and the upper portion tapered toward the throat,

and a valve cage assembly adapted to form a tight fit in the tapered portion of said housing, said assembly including a body portion in the form of a truncated cone, head and base plates attached to the top and bottom respectively of said body portion and protruding beyond the conical surface thereof, the periphery of both plates being beveled to coincide and form a tight fit in the internal taper of said housing, a conical passage formed by the internal surface of said 10 housing and the external surface of said cage, a conical valve chamber, a ball valve located in said chamber, a central opening in said base plate through which the said ball valve will pass in assembling the device, a valve seat bushing having a nipple portion providing a seat for said ball valve and adapted to be retained in said central opening by pressed fit to complete said valve cage assembly, a plurality of orifices in said conical body leading from said valve chamber 20 to said conical passage adjacent the lower end of the conical body and perpendicular to the longitudinal axis of said cage assembly, a plurality of orifices in said head plate adjacent the periphery thereof leading from the said conical 25 passage to the throat portion of the housing and being parallel with the longitudinal axis of said cage assembly, the first plurality of orifices being so disposed in relation to the second plurality of orifices to form an acute angle communication 30 therebetween for preventing tampering with the valve.

WALTER KEENAN.
